CASKET OR THE LIKE

Joseph E. Peter, Cincinnati, Ohio, assignor to The Crane
& Breed Casket Company, Cincinnati, Ohio, a corpora-
tion of Ohio

Filed July 21, 1967, Ser. No. 7,921

Term of patent 14 years

Int. Cl. D31

U.S. Cl. D19—1

FIG. 1 is a perspective view of a casket showing my new design;

FIG. 2 is a perspective view of the side and end opposite to those shown in FIG. 1;

FIG. 3 is a top plan view;

FIG. 4 is an enlarged, fragmentary and partially broken away elevational view of one of the handle portions shown in FIG. 1;

FIG. 5 is a top edge view of the handle portion shown in FIG. 4;

FIG. 6 is a bottom edge view thereof;

FIG. 7 is an elevational view as seen from the right end of FIG. 4; and

FIG. 8 is a sectional view taken on line 8-8 of FIG. 4.

The essential features of my design reside in the handle portions shown in solid lines; the other portions of the casket shown in dot-dash lines in FIGS. 1-3 being conventional.

I claim:

The ornamental design for a casket or the like, as shown and described.
